UNITED STATES PATENT OFFICE.

MEYER KAPLAN AND HARVEY KRAUS, OF CHICAGO, ILLINOIS.

DESIGN FOR AN INDICATOR LAMP.

Application filed March 28, 1928. Serial No. 26,052. Term of patent 14 years.

To all whom it may concern:

Be it known that we, MEYER KAPLAN and HARVEY KRAUS, both citizens of the United States, and residing at 1549 North Wood Street, Chicago, in the county of Cook and State of Illinois, have invented a new, original, and ornamental Design for an Indicator Lamp, of which the following is a specification, reference being had to the accompanying drawings, forming a part thereof.

Figure 1, is a side elevation of an indicator lamp showing our new design;

Figure 2, is a top plan view of the same;

Figure 3, is a front elevational view of the same;

Figure 4, is a rear elevational view of the same; and

Figure 5, is a bottom plan view of the same.

We claim:

The ornamental design for an indicator lamp as shown.

Signed at Chicago, in the county of Cook, and State of Illinois, this 16th day of March, A. D., 1928.

MEYER KAPLAN.
HARVEY KRAUS.
